UNITED STATES PATENT OFFICE

JOHN SNEED, OF DETROIT, MICHIGAN, ASSIGNOR TO THE MIDLAND STEEL PRODUCTS COMPANY, OF CLEVELAND, OHIO, A CORPORATION OF OHIO

BRAKE STRUCTURE

Application filed August 1, 1927. Serial No. 209,685.

This invention relates to brakes, and particularly to a plural-shoe brake of the internal expanding type, and adapted for use in an automobile.

It is among the objects of my invention to economically construct a brake which is equally effective regardless of the direction of drum rotation; the parts of which are easily made and quickly assembled, which will have a self-energized or servo action and which uniformly distributes the wear throughout the entire lining surface.

Other objects include a system of anchorage along with a mounting for various shoes and the particular structure of the separate shoes.

Other objects will appear from the following description which relates to the accompanying drawings, a preferred form of my invention is illustrated herewith. The essential characteristics are summarized in the claims.

In the drawings, Fig. 1 is an elevation showing the general arrangement of the brake shoes; Fig. 2 is a section taken along the line 2—2 of Fig. 1; Fig. 3 is a section taken along the line 3—3 of Fig. 1; Fig. 4 is a section taken along the line 4—4 of Fig. 1; Fig. 5 is a section taken along the line 5—5 of Fig. 1; Fig. 6 is a section taken along the line 6—6 of Fig. 1.

Referring particularly to Fig. 1, I show the usual brake drum D within which are mounted shoes A, B and C. The shoes support suitable brake lining L. The shoes may be channelled in cross section (see Figs. 4, 5 and 6) and may have a lining supporting portion 10 and inwardly extending radial side flanges 11. I provide anchor pins or stops 15 and 16 against which the ends of the shoe B are drawn when the shoe is in idle position, by a suitable retracting spring 17 secured to the backing plate 20 (see Fig. 4) through the pin and bracket 21. The ends of the shoe B are cut away as at 18 and 19 leaving a radial edge and an inclined circumferentially extending edge. The corners are rounded to conform with the surface of the anchor pins. In this manner the shoe B may either pivot about either of the anchor pins or may move radially with relation to either

of them. When the shoe is retracted by the spring 17, the inclined surface at the ends of the shoe, engage the anchor pins so as to center the shoe in its retracted position. The anchor pins 15 and 16 (see Fig. 5) are carried by the backing plate 20 with suitable bracket 22.

A third anchor pin or stop member 30 is positioned between adjacent ends of the shoes A and C. Auxiliary retraction stop pins such as those shown at 30A are provided to locate the inner idle position of the shoes A and C. When the shoes A and C are in idle position, their ends are drawn against the pins 30 and 30A by the springs 31. In the form illustrated herewith, the ends of the side flanges 11 of the shoes A and C are squared and engage the flattened radial surfaces of the anchor pin 30 as at 32 and 33. In this manner the shoes A and C are limited in their circumferential movement relative to the pin 30, but are permitting a sliding radial movement therewith. The pins 30 and 30A may be suitably carried on the backing plate in any convenient manner; no particular embodiment is shown herewith.

To effect operation of the brake, means are provided for spreading the adjacent ends of the shoes A and C. I have illustrated a floating toggle arrangement (see also Fig. 2), which toggle may be actuated by a cable 35 or other suitable means. The cable is adapted to draw on the center pin 36 which engages the arms of the toggle 37 and 38. The arms of the toggle are bifurcated, both in a horizontal and vertical plane, and these arms in turn engage pins 39 and 40, which in turn are mounted in larger pins 41 and 42. The larger pins have flattened surfaces as at 43 on which the toggle arms may rest. The pins 41 and 42 are pivotally mounted in the side flanges 11 of the channel shaped shoes and are held in place by suitable means, such as cotter pins. The expanding means may float circumferentially and maintain a uniform expanding force, and is provided with a universal connection with the adjacent ends of the shoes A and C.

Referring particularly to Figs. 1, 3 and 4, I have illustrated the mounting for the other

ends of the shoes A and C. Extending between the side flanges 11 of the shoe B and pivotally mounted therein, is a pin 50 which in the form shown, is secured in the link or walking beam 60. A set screw 51 may be provided, if it is desired, to journal the pins in the side flanges rather than in the link. The link 60 may have circumferentially extending arms 61 and 62 which in turn carry pins 52 and 53. These pins may be held in place by set screws 54, or other suitable means. The pins 52 and 53 also pivotally engage extensions 65 and 66 of the side flanges of the shoes A and C. These extensions may be made integral with the shoes A and C, and I prefer to extend the side flanges and bring them closer together than the side flanges 11, so they may lie within the side flanges 11 of the shoe B, (see Fig. 6).

In operation, supposing the direction of drum rotation to be clockwise, the adjacent ends of the shoes A and C are spread by the toggle until the shoe C engages the drum and is forced both clockwise and downwardly as viewed in Fig. 1. This movement of the shoe C exerts a general downward force through the pin 53 and tends to lower the pin 50 along with the shoe B and to raise the pin 52 and the shoe A. The movement of the pin 50 is both radial and circumferential, so that the shoe B is either or both pivoted or slid along or around the anchor pin 15 into engagement with the drum throughout substantially its entire working length. The end of the shoe B adjacent the anchor pin 16 is moved outwardly from that pin. Meanwhile, the shoe A is forced against the drum and also forced against the anchor or stop member 30 so that to a limited extent, the pin 50 tends to follow a circle, of which the anchor 30 is the center. The pin 50 also tends to follow a circle, of which the anchor pin 15 is the center. In either event, the shoe C serves or acts as a servo shoe, for both the shoes A and B, and substantially 360° of lining engagement is effected. It will be seen that a similar operation follows if the direction of drum rotation is counter clockwise, in which event, the shoe A acts as a servo shoe for both of the other shoes.

It will be seen from the foregoing that a novel and eminently useful brake is provided. Certain modifications will appear to one skilled in the art without departing from the spirit of my invention. While I have shown a preferred form of my invention, I do not care to be limited in the scope thereof other than by the claims appended hereto.

I claim—

1. A brake having a pair of shoes and a link pivotally supported in its middle and connected at its ends to said shoes whereby movement of one of said shoes in one direc-

tion forces the other shoe to move in the opposite direction.

2. A brake having a pair of shoes and expansion means acting upon adjacent ends of said shoes, and a rocking link supported in its middle and in pivotal engagement at its ends with the other ends of said shoes, said link being bodily movable circumferentially of said drum.

3. In a brake, the combination of a plurality of shoes and means for expanding the shoes positioned between adjacent ends of two of the shoes, a link pivotally engaging the other ends of said shoes, said link being pivotally mounted in a third shoe.

4. In a brake, the combination of a shoe, a fixed anchor for one end of said shoe, a link pivotally mounted in said shoe, and a second shoe pivotally connected with said link and engaging the drum beyond said first named shoe and beyond said anchor.

5. In a brake, the combination of a brake shoe, an anchor disposed at each end of said shoe, a link pivotally mounted in said shoe, a pair of shoes each lying beyond the end of said first named shoe and having a pivotal connection with opposite ends of said link.

6. In a brake, the combination of a brake shoe, an anchor disposed at each end of said shoe, a link pivotally mounted in said shoe, a shoe lying beyond the end of said first named shoe and having a part bridging said anchor and pivotally connected with one end of said link.

7. In a brake, the combination of a shoe being channeled in cross section, having inwardly extending radial side flanges remote from the ends of said shoe, a pin journalled in said side flanges, a link mounted on the pin and rockable within said side flanges, means connected with said link for moving said shoe.

8. In a brake, the combination of a shoe being channeled in cross section, having inwardly extending radial side flanges, a pin journalled in said side flanges in the mid portion of said shoe and a link mounted on the pin and rockable within said side flanges.

9. In a brake, the combination of a brake shoe being channeled in cross section and having inwardly extending radial side flanges, the ends of said side flanges being cut away, said side flanges having a pair of aligned openings at the mid portion of said shoe, anchoring pins engaging the said cut away ends of the shoes and a pin pivotally mounted in said aligned openings.

10. In a plural shoe brake, a pair of shoes, anchoring means disposed between adjacent ends of said shoes, circumferential extensions formed on the other ends of said shoes, a third shoe, a link having a pair of arms and pivotally mounted in said shoe, the ends of the

arms of said link pivotally connected to said extensions.

11. In a plural shoe brake, the combination of a brake drum, a pair of shoes mounted within said drum, anchoring means disposed between the ends of said shoes, means for spreading the said ends of said shoes positioned adjacent said anchoring means, said shoes engaging said anchor along radial surfaces, a link pivoted in its mid portion and connected with the other ends of said shoes whereby a downward motion of one of said shoes tends to cause an upward motion of the other of said shoes along the said radial surfaces of said anchor.

12. In a plural shoe brake, the combination of a pair of shoes, anchoring means disposed between the ends of said shoes, said shoes engaging said anchor along radial surfaces, a link pivoted in its mid portion and connected with said shoes at its ends whereby a downward motion of one of said shoes tends to cause an upward motion of the other of said shoes along the said radial surfaces of said anchor.

13. A plural shoe brake, the combination of three shoes, two of said shoes being similarly formed, means disposed near the adjacent ends of said similarly formed shoes for limiting the circumferential movement thereof, a third shoe and a link pivotally carried thereby and connected to the other ends of said two shoes, means disposed at both ends of said third shoe for limiting circumferential movement and inward radial movement of said third shoe, and means for drawing said shoes inwardly when said brake is idle.

14. The combination of a brake drum, a plurality of shoes disposed in operative relation with said drum, one of said shoes being anchorable at either end and operatively connected with the others of said shoes, said first named shoe being channeled in cross section and having inwardly extending radial side flanges and a lining supporting portion, said side flanges being cut away near the ends of said shoe along a radial line and thence along a line inclined relative to the lining supporting portion of the shoe to the end of the shoe, anchor pins disposed at the ends of said shoe and adapted to be engaged by the cut away ends of said shoe and means for drawing said shoe against said anchor pins when the brake is idle.

15. In a plural shoe brake, the combination of a pair of shoes, anchoring means disposed between the ends of said shoes, said shoes engaging said anchor along radial surfaces, a link pivoted in its mid portion and connected with said shoes at its ends whereby a downward motion of one of said shoes tends to cause an upward motion of the other of said shoes along the said radial surfaces of said anchor, and a third shoe having inwardly

extending side flanges for supporting said link.

16. In a plural shoe brake, the combination of a pair of shoes, anchoring means disposed between the ends of said shoes, said shoes engaging said anchor along radial surfaces, a link pivoted in its mid portion and connected with said shoes at its ends whereby a downward motion of one of said shoes tends to cause an upward motion of the other of said shoes along the said radial surfaces of said anchor, and a third shoe anchorable at least at one end and pivotally supporting said link.

17. In a plural shoe brake, the combination of a pair of shoes, anchoring means disposed between the ends of said shoes, said shoes engaging said anchor along radial surfaces, a link pivoted in its mid portion and connected with said shoes at its ends whereby a downward motion of one of said shoes tends to cause an upward motion of the other of said shoes along the said radial surfaces of said anchor, a pair of separate anchor pins not engaged by said shoes and a third shoe positioned between said anchor pins and engageable with at least one of them, said third shoe supporting said link.

In testimony whereof, I hereunto affix my signature.
